CLAIM

The ornamental design for a combination USB hub and wireless keyboard, as shown and described.

DESCRIPTION

FIG. 1 is a front perspective view of the combination USB hub and wireless keyboard showing my new design;
FIG. 2 is a rear perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is another perspective view thereof, showing a closed position.

The dashed broken lines in the figures depict portions of the combination USB hub and wireless keyboard that forms no part of the claimed design.
